(57) **CLAIM**

The ornamental design for a snap-in articulator insert for easy release of stone model, as shown and described.

DESCRIPTION

FIG. 1 is a frontal perspective view showing a snap-in articulator insert for easy release of stone model according to my new design, the snap-in articulator insert being shown as attached to an articulator which is shown as environment and which does not comprise a part of my design;

FIG. 2 is a top plan view thereof;

FIG. 3 is a sectional elevation view thereof, as seen along the line 3—3 in FIG. 2, and showing the articulator insert connected to an articulator which is shown for environment purposes only;

FIG. 4 is an anterior elevation view thereof;

FIG. 5 is a posterior elevation view thereof;

FIG. 6 is a bottom plan view thereof; and,

FIG. 7 is a side elevation view thereof, the opposite side being identical.

The broken lines shown in the figure drawings represent environment, are for illustrative purposes only and form no part of the claimed design.
